(57) **CLAIM**

The ornamental design for a seat for a folding chair, as shown and described.

DESCRIPTION

FIG. 1 is a left side perspective view for a seat for a folding chair showing our new design;

FIG. 2 is a front view of the seat for a folding chair shown in FIG. 1;

FIG. 3 is a rear view of the seat for a folding chair shown in FIG. 1;

FIG. 4 is a right side view of the seat for a folding chair shown in FIG. 1;

FIG. 5 is a left side view of the seat for a folding chair shown in FIG. 1;

FIG. 6 is a top view of the seat for a folding chair shown in FIG. 1; and,

FIG. 7 is a bottom view of the seat for a folding chair shown in FIG. 1.

The broken line illustrations in the drawing figures of the chair frame and seams in FIGS. 1-7 are for illustrative purposes only and form no part of the claimed design.
